UNITED STATES PATENT OFFICE.

JASON C. LOTTERHAND, OF NEW YORK, N. Y., ASSIGNOR TO THE UNION TYPEWRITER COMPANY, OF JERSEY CITY, NEW JERSEY, A CORPORATION OF NEW JERSEY.

TYPE-WRITING MACHINE.

SPECIFICATION forming part of Letters Patent No. 684,645, dated October 15, 1901.

Original application filed August 7, 1897, Serial No. 647,414. Divided and this application filed April 10, 1899. Serial No. 712,476. (No model.)

To all whom it may concern:

Be it known that I, JASON C. LOTTERHAND, a citizen of the United States, and a resident of the borough of Manhattan, in the city of New York, in the county of New York and State of New York, have invented certain new and useful Improvements in Type-Writing Machines, of which the following is a specification.

10 This application is a division of my application for Letters Patent of the United States filed August 7, 1897, Serial No. 647,414.

15 The present invention relates more particularly to that class of type-writing machines known as "visible-writing" machines, being machines in which the work as it progresses is visible to the operator, as distinguished from those machines in which the work can only be observed by lifting the paper-carriage 20 or platen or otherwise moving it to abnormal position for that purpose.

25 One object of the invention is to have the work as it progresses in plain view of the operator, so that he may observe the same without craning the neck or moving any portion of the body.

Another object of the invention is the production of a machine which shall be simple in construction and comparatively cheap to 30 manufacture, which shall be of less size and weight than other machines now in use and having a similar capacity, and which shall embody novel conveniences and improvements, including a mode of mounting the key-35 levers upon a fulcrum-rod so that any lever may be readily detached, an arrangement of key-levers such that they may be directly connected by upright devices to a system of type-bars which occupies much less trans-40 verse space upon the machine than the keyboard, a type-guide which automatically moves away from the printing-point after each impression is made, so as to disclose the writing, a ribbon-guide fixed to said type-45 guide and moving therewith, the connections between the key-levers and the said combined type and ribbon guide being such that the guide reaches working position before the impression is made and remains at such position 50 during the completion of the type-stroke, and

also a novel construction of thin type-bar bearing by which the type-bar is directly supported upon a short pivot and is prevented from sidewise vibration by a series of bearing-balls placed between the side of the type-bar hub and the side of the hanger, by which construction the type-bar may be guided in its movements with sufficient accuracy, while danger of binding or clamping between the type-bar and the hanger is avoided.

To these ends the invention includes features of construction and combinations of devices, all as will be hereinafter described, and more particularly pointed out in the appended claims.

The preferred form of the invention is illustrated in the accompanying drawings, forming part of this specification, in which—

Figure 1 is a plan view of a machine in which the present invention is embodied, certain parts not connected with the invention being omitted. Fig. 2 is a bottom view of said machine. Fig. 3 is a longitudinal vertical sectional view. Fig. 4 is an enlarged sectional elevation of a fragment of the type-segment, 75 showing the construction of and mode of fastening the type-bar hanger as well as a portion of the type-bar and its connecting-link. Fig. 5 is a front sectional elevation of a portion of the type-bar segment, showing the 80 mode of securing the type-bar hangers thereon. Fig. 6 is an enlarged plan of the right-hand end of the type-bar segment, showing several of the hangers and type-bar hubs. Fig. 7 is an enlarged sectional view of the 85 bearing for the type-bar. Fig. 8 is a detail of the ribbon and type guide mechanism.

The same numeral of reference will be used to designate the same part in the various views of the drawings.

1 indicates a rectangular base or frame having a top plate 2 at the rear and a cross-bar 3 toward the front of the machine.

4 is a forwardly and rearwardly movable plate or frame guided by tracks 5 at the tops 95 of the sides of the frame 1.

6 represents carriage-guide rails borne by brackets 7, secured to the top of the plate or frame 4, and 8 is a carriage guided by said rails 6 and carrying a platen 9.

10 marks type-key levers, and 11 marks space-key levers. The levers 10 are provided with finger-pieces 12 at their forward upturned ends, and the space-key levers 11 are connected by a space-key 13, extending across the front of the keyboard and limited in its downward movement by stops 14, secured to the front end of the frame 1. The key-levers 10, preferably stamped from sheet metal, are fulcrumed at their extreme rear ends upon a rod 15. The front ends of the key-levers 10 are suitably spaced to accommodate the finger-buttons 12, while in rear of the keyboard the levers are bent inwardly toward the middle line of the machine for a purpose presently to be explained and at their rear ends are brought close together and parallel with each other, being confined against lateral motion upon their fulcrum-rod 15 by two of the supports 16 for said rod. Immediately in rear of the keyboard the key-levers 10 fit between and are guided in their vertical movements by a series of vertical pins 17, depending from the frame-bar 3 aforesaid. For convenience in assembling and to permit the easy removal of any one of the key-levers 10 without the others the rear ends of the levers are provided with slots 18, opening into the holes through which the fulcrum-rod 15 passes, and the rod 15 is flattened upon its rear and front sides and is so mounted in its supports that it can be turned a quarter-revolution to bring its flattened sides parallel with the slots in the key-levers. The vertical thickness of the rod 15 when turned with its flattened sides parallel with the slots in the key-levers is such that any of the levers may be readily disconnected from it by drawing the lever forward, and the lever may be replaced with equal facility and there secured in place by turning the rod up to normal position. In originally assembling the parts of the machine the rod 15 may be put in place before the key-levers are assembled and the latter be then connected to it in the manner indicated. The parallel parts of the key-levers 10 at the rear of the machine form mutual guides for any key-lever that is operated. It will be noted that the key-levers are fulcrumed at their rear ends and at right angles to a single axis or rod and that they diverge sharply toward the front of the machine and become parallel at the keyboard-space. The type-bars 19 carry type-blocks 20, which in the instance shown are provided each with two types, as "upper" and "lower" case characters. The type-bars are arranged in the arc of a circle in front of the platen 9 and intermediate the same and the keyboard of the machine. The type-bars 19 are of uniform size and shape and are pivoted at near their lower ends upon the inner rear ends of type-bar hangers 21, which consist of thin plates stamped from sheet metal and composed of an outer or forward horizontal portion and an upturned rearwardly-curved portion. The forward portions of these hangers 21

are seated in radial slots formed in the upper side of a segment or an arc-shaped support 22, which is secured at its opposite ends to the main frame 1 of the machine. The plane of the segment 22 is horizontal, and the type-bar hangers 21 are so arranged that the pivots of the type-bars are in front of and below the level of the axis of the platen 9. The type-bars 19 are curved forwardly and upwardly of the machine and are of a length such that their type coat with the platen 9, near the top thereof. The lower inner end of each type-bar 19 is connected by a wire 23 to its corresponding key-lever 10 beneath it, and by means of the arrangement of the key-levers 10 shown in Fig. 2 and hereinbefore described the type-bars 19 may be connected to their corresponding operating-levers 10 at points 24 immediately beneath such type-bars, so that the connecting-wires 23, which, it will be noted, are arranged in an arc at their points of connection with the key-levers as well as with the type-bars, are straight and of equal and minimum length and stand in an approximately vertical position, thus permitting a direct and approximately uniform application of the power of all the key-levers to their respective type-bars. The pivots of the type-bars are arranged in a horizontal plane and preferably below the horizontal plane through the printing-point. The arc in which the type-bars 19 are thus pivoted is in front of the platen, and the type-bars flare upwardly and outwardly and rest in inclined positions relatively to the top of the platen and are thus brought low down, with the type ends occupying a larger arc than the arc formed by their pivots, by which construction and arrangement the operator is enabled to view the printing-point without craning the neck or moving from natural working position. The type-bar hangers 21 are held in place in their slots 25 in the segment 22 by the means shown on an enlarged scale in Figs. 4, 5, and 6, said figures being on a uniform scale larger than the scale of Fig. 3. The horizontal portion of each hanger 21, which fits in the slot 25 in the frame 22, is of such width that its upper edge projects slightly above the upper surface of said frame 22. The slots 25 are radial with the printing-point and are arranged in pairs, the members of each pair being closer to each other than either member is to a member of an adjacent pair of slots. In other words, the walls 26, separating members of the same pair of slots 25 from each other, are thicker than the walls 27, separating the members of adjacent pairs of slots. The segment 22 is provided with perforations 28, lying between the members of each pair of slots 25 and passing through the walls 26, as shown more clearly in Fig. 6. There is provided a flat plate 29 for each pair of hangers, resting in each pair of slots 25, the said plate resting upon the slightly-projecting upper edges of the said hangers and the said plate 29 extending

outwardly beyond the edge of the frame 22. Bolts 30 are passed upwardly through the openings 28 and through the overlying plates 29. The bolts 30 are provided at their lower ends with heads, which bear against the lower surface of the frame 22, and the bolts are screw-threaded at their upper ends and have nuts 31 screwed upon them, which nuts bear on the tops of the plates 29. The wall between the pairs of slots 25, and so between the pairs of hangers 21, is slightly less than the diameter of the bolt 30, and the opposite sides of the bolt are flattened to permit its passage between the hangers, the contact of the hangers with the flattened sides of the bolt then holding the bolt in fixed position while the nut 31 is screwed tightly upon its upper end, and the plate 29 is firmly clamped against the two edges of the hangers upon which it bears, thus securely holding them in place. The extreme outer ends of the plates 29 are provided with upturned ears 32, to which are connected the outer ends of the coiled springs 33, which serve to yieldingly hold the type-bars in and to return them to normal position, the inner ends of said springs being connected to the type-bars at points outside of and slightly above their pivotal connection with the hanger-plates 21, as seen in Figs. 3 and 4. The friction of the pivotal connection of the type-bars of the hangers is relieved by ball-bearings, the arrangement of which will be next described, reference being had more especially to Figs. 6 and 7. Each of the hangers 21 is provided at its upper inner end with a threaded hole into which is screwed one end of a short screw 34, whose head is beveled at its side adjacent the hanger and which is provided with a cylindrical body 35 intermediate the head of the screw-threaded portion, said cylindrical body 35 being of a diameter greater than that of the screw-threaded portion. The connection of the bar to the hanger affords a bearing for the type-bar which occupies very little space laterally and enables the entire series of type-bars and hangers to be arranged in compact order in less than one-third of a circle, while at the same time the comparatively large diameter of the bearing affords a rigid support for the type-bar against lateral play and serves to preserve the alinement of the types. Any type-bar and its hanger may be readily removed for the purpose of tightening up its screw 34 or for any other purpose by unscrewing the nut 31 upon the upper end of the bolt 30 adjacent such hanger and removing the plate 29, which is held in place by said nut, and by disconnecting the type-bar from its resetting-spring 33 and connecting-wire 23. The slots in the frame 22, in which the hangers 21 fit and are secured, are truly radial to the printing-point, and in assembling the type-bars the alinement may be readily attained by adjusting the hangers 21 back and forth in the slots and then securing them in place by means of the plates 29, bolts 30, and nuts 31. The hanger 21 has formed upon its side adjacent the type-bar 19 a circular V-shaped groove 39 for the reception of the balls 37, the balls being held in place by the flat surface of the type-bar 19, which is provided with a small hole fitting upon the screw 34. The type-bar 19 is also provided with a slight circular boss 40, provided with a cylindrical bore, within which the cylindrical portion 35 of the screw 34 passes. The balls 37 are in a circle of a diameter greater than that of the head of the screw 34 and bear against the side of the type-bar 19. Under this construction the type-bar is not supported wholly upon the balls; but the provision of the balls interposed between the type-bar and hanger in a circle concentric to the pivotal axis of the type-bar permits the mounting of the type-bar upon a small pivot, as screw 34, so that the friction between the type-bar and its pivot is very slight, while the comparatively large circle of balls interposed between the type-bar and hanger furnishes a large bearing between the two to rigidly hold the type-bar against lateral play without materially increasing the friction between the type-bar and hanger. The desideratum sought is to reduce the lateral width or thickness of the bearing to a minimum in order to permit the most compact arrangement of the series of type-bars and hangers and at the same time provide a frictionless bearing of large diameter between each type-bar and its hanger to prevent lateral play of the type-bar and preserve the alinement. The hub portions of the hanger 21 and the type-bar 19 may be regarded as a pair of plates. The conical head of the screw or pivot-pin 34 holds the type-bar hub upon the pivot-pin and also cooperates with the bearing-balls to steady the type-bar laterally in its swinging movement toward the platen. The annular groove 39 is preferably of such diameter that the balls do not contact with the pivot-pin 34. Preferably the type-bar turns partly upon the conical head of the screw 34 as a pivot and partly upon the shoulder or body portion 35 of the screw. When in normal position, the type-bars 19 rest at their outer edges against a curved type-bar rest 41, supported at its opposite ends upon the frame 22 by means of downwardly-extending arms 42.

The next feature of this branch of my invention relates to a movable type-guide adapted to be moved into and out of the path of the types at the printing-point, and the same will next be described. The type-guide shown in the drawings comprises a frame 43, provided with an elongated opening or slot 44 of suitable size and shape to permit the passage through the plate of the types upon the ends of the type-bars and having slightly-beveled walls to coact with the type-blocks 130 to center the type as they strike the platen-roller 9. The frame 43 is pivoted at 45 in lugs or ears 46, extending forwardly and upwardly from a curved post or standard 47,

which is attached to the frame 4, hereinbefore mentioned. The frame 43 comprises a body having the guide-slot 44 and two downwardly-extending arms 48, which are joined 5 by a cross-piece 49, which is extended beyond the arms 48 and is bent back parallel to itself, as shown at 49^a in Fig. 1, to provide a ribbon-guide and also bearings for the pins or screws 45, hereinbefore mentioned. The cross-bar 10 49 is provided with a forwardly and downwardly turned arm 50, to which the upper ends of two links 51 are pivotally connected. The lower ends of the links 51 pass down outside the two parallel standards 52, rising 15 from the base of bracket or standard 47, and the standards 52 are provided with slots 53, extending upwardly and slightly rearwardly. The lower ends of the rods 51 are united by a cross-pin or screw 54, which passes through 20 the slots 53 and forms an axis for a roller 55, which lies between the brackets 52. A spring 56, having one end connected to one of the rods 51, near the upper end thereof, and the other end connected with the brackets 52, 25 serves to normally draw the rods 51 downwardly until the pin 54 rests in the bottom of the slots 53, thus holding the guide-frame 43 in the position shown in Figs. 3 and 8. A lever 57 is pivoted at 58 between the standards 30 52 aforesaid, the point or axis 58 being on a level higher than the level of the lower ends of the slots 53, and the lever 57 is provided with a curved notch or cam 59, adapted to coact with the front and underneath portion of the roller 55 as the rear end of the 35 lever 57 is raised, and so to force the rods 51 endwise and upwardly, thus throwing the frame 43 rearwardly toward the platen 9 until such time as the circular end 60 of the 40 lever 57 passes beneath the roller 55, after which the continued motion of the lever 57 exerts no further lifting action or power upon the rods 51, since the center of end 60 lies in the axis 58 of lever 57. A rod 61 is pivotally 45 connected to lever 57 at its front end, and the other end of the rod 61 is similarly connected to a cross-bar 62, lying underneath the key-levers 10, said bar 62 forming the middle portion of a bail whose ends are pivoted to the 50 frame 1 at 63.

The operation of the foregoing devices is as follows: Upon the depression of a key-lever 10 its corresponding connecting-rod 23 is drawn downward, thus drawing down the 55 rear end of the corresponding type-bar and throwing the type thereon rearwardly and toward the printing-point, and at the same time the key-lever depresses the bail 62 and through the rod 61 draws down the forward 60 end of the lever 57, thus causing the cam portion 59 of the lever to push the roller 55, pin 54, and rods 51 upwardly against the force of spring 56. The endwise motion of the rods 51 causes a rearwardly-swinging motion of 65 the guide-frame 43 until such time as the "dwell" portion 60 of the lever 57 comes into coaction with the roller 55, at which time the

guide-frame 43 lies closely adjacent the platen 9. The guide-frame 43 reaches the described position and comes to rest under the influence 70 of the spring 56 and the dwell 60 before the type-bar has completed its printing movement; but the continued downward movement of the key-lever to bring the type on the said bar to the printing-point exerts no 75 turning effect upon the type-guide frame. As the type approaches the printing-point the guide 43 coacts with the type-block 20 to center the type, which passes through the opening 44 and makes its impress upon the substance of the platen 9 by means of an inking-ribbon. Upon the release of the depressed key-lever the springs 33 and 56, aided by the spring 64, connecting a universal bar 65 with the frame 4, restore the type-bar, key-lever, and type-guide and bail 62 to normal 80 position, and at the return movement of the parts the type-bar moves forward in advance of the type-guide. The inking-ribbon hereinbefore mentioned is marked 66 and is 85 guided in any suitable way to and between the cross-bar 49 and the arm 49^a at one side (say the left-hand) and upward in front of the bar 43 at that side and around an edge 67 thereof and across in rear of the said bar 95 43 to a similar edge 67^a at the other side, at which point it passes to the front and then down to and between the arm 49^a and cross-piece 49 at the right-hand side and away to a ribbon-spool. (Not shown.) In this manner 100 the frame 43 also serves as a ribbon-guide; but this feature of my invention is specifically claimed in a companion application, filed April 10, 1899, Serial No. 712,477. The construction of the lever 57 and the arrangement 105 by which it gives a uniform throw to the type-guide 43 also serves to prevent variations in the movement of different key-levers from effecting the throw of the type-guide. A more simple connection between the lever 57 and the vibratory type-guide would be to pivot the lower end of the link 51 directly to the rear end of the lever 57; but the described construction is preferable for the reasons just stated. Under the connection hereinbefore described, 110 after any key-lever has been moved a sufficient distance to cause the curve or cam portion 59 in the rear end of the lever 57 to clear the roller 55, which it has lifted, it is immaterial to the operation of the type-guide 115 whether such key-lever moves any farther or not, such farther movement having no effect upon the type-guide. The form of connection shown also permits the type-guide to come to rest upon the platen-roll before the 120 movement of the key-levers and type-bars ceases; but this might be accomplished even were the rod 51 directly connected to the lever 57. This feature of my invention is not restricted, however, to any particular connection 125 between the key-levers and type-guide for operating the latter. The carriage 8 is drawn forward by a spring (not shown) and is provided with a rack-bar 68. The rear rail

6 is provided with standards 69, in which a shaft 70 is journaled, and the shaft 70 is provided with escape-dogs 71 of any suitable construction and adapted to coact with the rack 5 68. A connection 72 between an arm on the shaft 70 and the universal bar 65 communicates motion to the shaft and dogs whenever a key-lever is operated.

What I claim as new, and desire to secure 10 by Letters Patent, is—

1. In a type-writer, the combination of a normally stationary fulcrum-rod having flattened sides and mounted to turn in its supports, and key-levers having holes through 15 which said rod passes and slots between said holes and the pivoted ends of the levers, the construction and arrangement being such that when the rod is in normal position none of the levers can be removed therefrom and 20 also such that the rod may be turned to present its edge to all of said slots simultaneously, so that any lever may be withdrawn by an endwise movement, without disturbing any of the other levers, substantially as and 25 for the purpose described.

2. The combination of key-levers fulcrumed at their rear ends and at right angles to a single axis or rod and diverging sharply toward the front of the machine and becoming parallel at the keyboard-space, type-bars pivoted in the arc of a relatively small circle above the diverging portions of the key-levers and flaring upwardly and outwardly whereby the type-bars when at rest occupy inclined positions with their type ends flaring outwardly and occupying an arc of greater radius than the arc of the pivots, and straight, parallel vertical wires connecting the type-bars directly with the respective key-levers at points 35 immediately beneath the type-bars, substantially as described.

3. The combination of key-levers fulcrumed at their rear ends and having straight front and rear ends, the rear ends of the levers fitting closely together and guiding each other and their front ends being spaced apart to accommodate the finger-buttons, and the two portions of the levers being connected by the intermediate converging portions, guide-pins 45 between which the straight front ends of the levers are vertically guided, type-bars mounted in the arc of a circle above the converging middle portions of the key-levers, vertical wires connecting the respective type-bars directly with the converging portions of the levers beneath them, and resetting-springs connected to the type-bars, substantially as described.

4. In a type-writing machine, the combination of a platen, a series of type-bars pivoted in an arc in front of the platen and striking downwardly, said arc being substantially concentric with the printing-point and lying in a substantially horizontal plane which is below 50 the plane of the printing-point, and said type-bars diverging upwardly and forwardly from said pivot-arc, whereby an unobstructed

view of the printing-point is afforded and each type impression may be seen as soon as made, and means for operating said type-bars. 70

5. In a type-writing machine, the combination of a platen, type-bars pivoted in the arc of a circle below the horizontal plane through the printing-point and striking rearwardly and downwardly upon the upper surface of 75 the platen and also flaring upwardly and outwardly, and said pivot-arc being substantially concentric with the printing-point, a vibratory ribbon-carrier for covering and uncovering the printing-point during the operation 80 of the machine and the whole affording an unobstructed view of the printing-point during the progress of the writing, key-levers, and connections for operating said bars and said ribbon-carrier, substantially as described. 85

6. In a type-writing machine, the combination of a platen, rearwardly and downwardly striking type-bars pivoted in the arc of a circle in front of said platen and beneath the 90 horizontal plane through the printing-point, said type-bars flaring upwardly and outwardly and affording an unobstructed view of the printing-point during the progress of the writing, key-levers pivoted at their rear 95 ends and diverging toward the front of the machine, and straight, parallel vertical connecting rods or wires between said diverging parts of said levers and said type-bars, substantially as described. 100

7. In a type-writer, the combination of key-levers fulcrumed at their rear ends and converging toward the middle line of the machine in rear of the keyboard-space, a type-bar-hanger frame located above the converging 105 portions of the key-levers and curved in the arc of a circle concentric to the printing-line and provided with a series of slots radial to said point, a series of type-bar hangers fitting in said slots, means for holding them in 110 place, a series of type-bars of substantially uniform size and shape pivotally mounted upon said hangers in a single curved line concentric to the printing-point, direct connections between the type-bars and the respective key-levers beneath them, and resetting-springs 115 connected to the type-bars.

8. The combination of the radially-slotted frame the type-bar hangers having horizontal forward portions fitting in the slots in the 120 frame and projecting above the upper surface of said frame and having the upwardly-projecting rear portions, plates resting upon the upper edges of the horizontal portions of the hangers, bolts passed upward through the 125 frame and plates between the adjacent hangers and having the flattened sides engaged by the adjacent hangers, nuts screwed upon the upper ends of the bolts and bearing upon the plates, type-bars mounted upon 130 the upper ends of the hangers, and springs connected at their inner ends to said type-bars and at their outer ends to the plates, substantially as described.

9. The combination of key-levers fulcrumed at their rear ends and having converging middle portions, a type-bar-hanger frame curved in the arc of a circle above the converging 5 portions of the key-levers and provided in its upper surface with a series of slots radial to the printing-point, type-bar hangers secured in said slots, type-bars of substantially uniform size and shape pivotally mounted upon 10 said hangers, wires connecting the type-bars with the key-levers beneath them, and resetting-springs connected to the type-bars, substantially as described.

10. The combination of a main frame, key- 15 levers pivoted at the rear thereof and diverging toward the front of the frame, an arc-shaped type-bar-supporting frame located above the diverging portions of the key-levers and attached to said main frame, a series of type-bars pivotally connected with 20 said arc-shaped frame and flaring upwardly and outwardly, connections between said type-bars and said key-levers, a backwardly and forwardly moving frame mounted on the 25 main frame and carrying a laterally-movable paper-carriage, letter-spacing mechanism carried by said moving frame and by said carriage, and mechanism connecting the letter-spacing mechanism with the key-levers, 30 substantially as described.

11. The combination of a main frame, a type-bar-supporting arc-shaped frame attached thereto, upwardly and outwardly flaring type-bars pivotally connected to said 35 frame in a horizontal plane and striking rearwardly and downwardly, a laterally-moving paper-carriage in rear of said type-bars and having the printing-point above the horizontal plane of the pivots of said bars, and carrying part of the letter-spacing mechanism, a vibratory ribbon-guide for covering and uncovering the printing-point, a backwardly and forwardly moving frame mounted on the main frame and carrying the paper-carriage, said 45 ribbon-guide and part of the letter-spacing mechanism, key-levers pivoted on the main frame, and connections between said levers and the type-bars the vibratory ribbon-guide and the letter-spacing mechanism for operating the same, substantially as described.

12. In a type-writing machine, the combination of a movable type-guide, key-levers, type-bars actuated by said levers, and a lost-motion connection between said levers and 55 said guide, said connection being such that said type-bars may continue in motion after the type-guide has come to rest in its working position, substantially as described.

13. In a type-writing machine, the combination of a pivoted type-guide, key-levers, type-bars actuated by said levers, a universal bar operated by said key-levers, and a connection between said bar and said guide including two members of which one moves the 60 second through a given distance or to a given position to bring the guide into place for co-action with the type and then retains the sec-

ond member and guide in such positions during the remainder of its own forward motion and the remainder of the motion of the key-levers and type-bars, whereby the guide is moved to position adjacent to the platen and is stopped before the key-levers and type-bars complete their printing strokes, substantially as described. 70

14. In a type-writing machine, the combination of a pivoted type-guide, key-levers, type-bars operated thereby, and a connection between said key-levers and said guide including a cam provided with a "dwell" arranged to retain the guide in the position to which the working face of the cam moves it, whereby the guide is moved to a position adjacent to the platen and stops and is retained in such position by the dwell during the completion of the printing strokes of the key-levers and type-bars, substantially as described. 80

15. In a type-writing machine, the combination of a pivoted type-guide, a fixed standard provided with a guiding-slot, a connecting-rod pivotally connected to said type-guide and guided by said slot in its own endwise motion, a lever provided with a cam having a working face and a "dwell" for moving said rod endwise along said slot and retaining it 90 in the position to which it is moved, key-levers, type-bars operated thereby, connections between said levers and said cam-lever, and a returning-spring, substantially as described. 95

16. In a type-writing machine, the combination of a pivoted arm provided with a type-guide and ribbon-guiding arms, key-levers, type-bars actuated thereby, and a lost-motion connection between said levers and said pivoted arm, said connection being such that 105 said type-bars may continue in motion after the type-guide has come to rest in its working position, substantially as described. 100

17. In a type-writing machine, the combination of a pivoted arm provided with a type-guide and with ribbon-guides, key-levers, type-bars operated thereby, and connections between said levers and pivoted arm, including a cam provided with a "dwell" arranged to retain the guide and carrier in the position 110 to which the working part of the cam moves them, whereby they are moved to a position adjacent to the platen and stop and are there retained by the said dwell, substantially as 115 described. 120

18. In a type-writing machine, the combination of a pivoted arm provided with a type-guide and with ribbon-guides, a fixed standard provided with a guiding-slot, a rod pivotally connected to said arm and guided by 125 said slot in its own endwise motion, a lever provided with a cam comprising a working face and a dwell for moving said rod endwise along said slot and retaining it in the position to which it is moved, key-levers, connections between said levers and said cam-lever, type-bars operated by said key-levers, and a spring for retracting said pivoted arm, substantially as described. 130

19. The combination of a type-bar hanger having a flat arm provided with a threaded hole, a bevel-headed screw engaging with said hole, a flat type-bar perforated to fit closely 5 said bevel-head and a set of antifriction-balls interposed between the type-bar and the hanger and running in a raceway in one of said parts.

20. The combination of a type-bar hanger 10 having an arm, a bevel-headed screw engaging with a threaded hole in said arm and providing a relatively small pivot, a type-bar engaging at one side thereof with said pivot or screw, so as to be held on by the latter, and a 15 set of antifriction-balls running in a raceway exterior to the said pivot and lying between the hanger and the other side of the type-bar.

21. In a type-writing machine, the combination of a pair of plates, one fixed upon the 20 machine and the other forming the hub of a type-bar, a pivot-hole in said type-bar hub, a pivot-pin engaging said pivot-hole and supported upon said fixed plate, and a set of bearing-balls surrounding said pivot-pin and arranged 25 between said plates, said pivot-pin having a head which holds said type-bar hub upon the pivot-pin and the construction and arrangement being such that said head co-operates with said bearing-balls to steady the 30 type-bar laterally.

22. In a type-writing machine, the combination of a pair of plates, one fixed upon the machine and the other forming the hub of a type-bar, a pivot-hole in said type-bar hub, 35 a pivot-pin engaging said pivot-hole and supported upon said fixed plate, an annular groove formed in the side of one of said plates

which faces the other of said plates, a set of bearing-balls placed between said plates and running in said groove, said balls being out 40 of contact with said pivot-pin, and said pivot-pin having a head which retains the type-bar upon the pin and co-operates with said bearing-balls to steady the type-bar laterally.

23. In a type-writing machine, the combination 45 of a pair of plates, one fixed upon the machine and the other forming the hub of a type-bar, a pivot-cone supported upon said fixed plate, and a set of bearing-balls supported between said plates, said cone and said bearing-balls co-operating to steady the type-bar laterally, and said type-bar pivotally engaging said cone.

24. In a type-writing machine, the combination 50 of a platen, type-bars arranged in an arc in front of said platen and extending upwardly and outwardly from their pivots so as to afford an unobstructed view of the printing-point during the progress of the writing, key-levers extending below said type-bars 55 and platen and diverging toward the front of the machine, and a series of connecting-rods extending from said type-bars directly down to said key-levers at their diverging portions, the points of connection between said connecting-rods and said key-levers being arranged 60 in an arc.

Signed at the United States consulate at Nottingham, England, this 22d day of March, 1899.

JASON C. LOTTERHAND.
